INVENTOR:

Charles L. Groda

By Horatio C. Ellsor

ATTORNEY.

UNITED STATES PATENT OFFICE.

CHARLES L. GRODE, OF PROVIDENCE, RHODE ISLAND.

STOP FOR SPRINKLER-HEADS.

No. 890,356.

Specification of Letters Patent.

Patented June 9, 1908.

Application filed August 16, 1907. Serial No. 388,917.

To all whom it may concern:

Be it known that I, CHARLES L. GRODE, a citizen of the United States, residing at Providence, in the county of Providence and 5 State of Rhode Island, have invented certain new and useful Improvements in Stops for Sprinkler-Heads, of which the following is a specification, reference being had therein to the accompanying drawing.

10 My invention relates to stops or plugs for the head of automatic fire extinguishers or sprinklers, and has for its objects, besides the ends commonly sought in this class of devices, a structure which is adapted to fulfil 15 the requirements of a combined and fusibly operative device; and a device capable of suitable insertion and adjustment in any size of sprinkler head.

Further objects are simplicity, strength, 20 convenience, and certainty of operation.

To the above ends my invention consists in the novel construction and combination of parts hereinafter described, and set forth in the accompanying drawings, wherein,

25 Figure 1 is a side elevation of my novel stop applied to a sprinkler head, the latter being shown partially in section Fig. 2, a like elevation of the stop shown independent of the sprinkler head, disclosing the side of the 30 stop opposite the side shown in Fig. 1. Fig. 3, a plan of the same, Fig. 4, a section on line *x x* of Fig. 2, Fig. 5, a perspective view of the stop head, and Figs. 6, 7, 8, and 9, detail views of the various interlocking members of 35 the stop.

Like reference characters indicate like parts throughout the views.

My novel device is described and illustrated as applied to a sprinkler head mounted 40 uprightly but is obviously adapted without change of form to a sprinkler head which is downwardly directed or inclined.

In the drawings is shown the usual sprinkler head comprising the usual screw 1, holder 45 2, retaining ring 3, diaphragm 4 provided with a circular opening 5, arch 6, and seat or bearing 7.

50 My novel device comprises a flat vertical plate 8, shown in detail in Fig. 6, having a curved portion 9 provided with a central perforation 10. The upper end has rectangular lateral lugs or ears 11 and an intermediate slot 12. Mounted upon the bottom of the plate 8 is a hollow hemispherical stop head 13 having a 55 transverse bar or pin 14. The latter traverses the opening 10 of the plate 8, and the

interior of the head conforms to the outline of the curved portion 9 of the plate 8. This particular form of head and connection with the plate is advantageous but not exclusive. 60

Resting upon the supporting plate 8 is a vertical connecting member or plate 15, shown in detail in Fig. 7. This plate has intermediate its length a rectangularly offset portion or shoulder 16 whereby is produced 65 oppositely directed parallel flat fingers 17 and 18. The upper finger, 17, is provided with an opening 19. In assembling the parts the offset or shoulder 16 rests loosely upon the plate 9 in its slot 12; the finger 18 resting against the face of the plate 9; and the finger 17 resting against the face of a hinged plate 20 which is shown in detail in Fig. 8. The plate 20 is provided in its top and bottom margins with rectangular notches 21 and 22 70 respectively; and at one end, with a pivot perforation 23. The portions of the plate upon each side of the notch 22 are bent laterally to form lugs or hooks 24. Upon the end of the plate opposite the perforation 23 is a 75 lateral ear 25 provided with a threaded opening 26. In assembling, the lugs 24 rest against the bottoms of ears 11; the notch 22 accommodates the offset or hooked portion 28 of a locking plate 29, shown in detail in 80 Fig. 9. This plate has a broad body portion, 30, integral with the offset portion 28, and the latter is provided with a lip 31 being in a plane substantially parallel with the plane of the body portion 30. The portions 90 28 and 31 form a hook adapted to enter the opening 19 of the plate 17 and engages this plate. The body 30 is fixed to the plate 20 by solder, as at 32 in Fig. 4. The solder is fusible at a predetermined degree of 95 temperature.

A pivot pin 33 passing through the perforation 23 connects the hinged plate 20 with the end of an arm 34. This arm is preferably formed by plates 35, 35, of similar contour 100 connected together by rivets 36, 36, but interspaced midway their lengths as at 37, and adjacent their hinged ends, as at 38. The pivoted ends of the plates 35 are curved for some distance; the curves ending in marginal depressions or cavities 39, 39, in vertical alignment with the stop head 13. The free end 40 of the arm 34 is sufficiently extended to form a comfortable hand hold. Obviously the arm 34 may be composed of a 105 single piece of material rather than of two riveted plates, it being understood that the 110

opening 37 is to be preserved therethrough. Mounted in the opening 37 in the arm 34 is an adjusting thumb screw 41 comprising a head 42, shoulders, 43, above and below the lever, and threads 44 upon its lower portion. The threaded portion of the screw 41 engages the threads of the opening 26, whereby the rotation of the screw causes the plate 20 and arm 34 to approach or recede from each other.

- 10 The stop mechanism, assembled as above set forth, is introduced into the sprinkler head as follows. The screw 41 is manually rotated to contract the pivoted or hinged parts 34 and 20 sufficiently to insert the head 15 13 into the discharge orifice 5 in the sprinkler head, and bring the depressions 39 of the arm 34 beneath the bearing or valve seat of the sprinkler yoke. The screw is then turned in the opposite direction, expanding the parts 20 and holding the same rigidly in position intermediate the seat 7 and diaphragm 4.

If, while my stop device is mounted as above described, the temperature reaches the degree essential for fusing the solder 32, 25 the member 29 will be released, and the pressure of the water will force the plates 8, and 15 upwardly thereby disengaging the hooks 18 and 31, and disassembling the stop parts. The sprinkler head then performs its usual 30 functions.

It will thus be observed that my novel stop performs the double functions of a stop and automatic sprinkler, and is adapted, by reason of the adjusting means, to any size 35 sprinkler head occasion may require.

While solder is shown only between two of the plates the same may be applied to other plates of my structure without departing from the spirit of my invention.

40 What I claim is,

1. In a sprinkler stop, the combination of a head, a bearing arm, and interlocking plates intermediate the head and bearing arm for disconnecting the head and arm under a pre- 45 determined degree of temperature.

2. In a sprinkler stop, the combination of a head, a bearing arm, and over-lapping plates connecting the head and bearing arm, and solder between the faces of two or more 50 of the plates.

3. In a sprinkler stop, the combination of a head, a bearing arm, and a series of inter-engaging plates pivotally fixed to the bearing arm and connected with the head, and solder 55 between two or more of the plates.

4. In a sprinkler stop, the combination of a supporting plate, a stophead mounted upon one end of the plate, ears upon the supporting plate, a hinged plate, lugs upon the

60 hinged plate engaging the ears, a bearing arm, a pivot member connecting the hinged plate and bearing arm, means for frictionally engaging the supporting plate and hinged plate, and a locking plate soldered to the hinged plate and engaging the friction en- 65 gaging means.

5. In a sprinkler stop, the combination of a head, and a bearing arm, a hinged plate pivotally connected with the bearing arm, 70 plates connecting the hinged plates and head, and means in the bearing arm and engaging the hinged member for adjusting the arm and hinged member.

6. In a sprinkler stop, the combination of a head, bearing arm, a hinged plate pivotally connected with the bearing arm, 75 plates connecting the hinged plate and head, and an adjusting screw connecting the bearing arm and hinged plate.

7. In a sprinkler stop, the combination of 80 a head, and a bearing arm, a hinged plate pivotally connected with the bearing arm, plates connecting the hinged plate and head, solder between the connecting plates, and means connecting the hinged plate and bearing arm for moving the hinged plate and arm 85 towards and away from each other.

8. In a sprinkler stop, the combination of a supporting plate, a stop head mounted upon one end of the plate, ears upon the supporting plate, a hinged plate, lugs upon the hinged plate engaging the ears a connecting plate resting upon the supporting plate provided with an offset portion intermediate its length, and provided with an opening, a 90 locking plate having a body portion adjacent the hinged plate, and a hook portion passing through said opening, solder between the hinged plate and the body portion of the locking plate, a bearing arm, a pivot pin 100 connecting the lever arm with one end of the hinged plate, and a screw connecting the lever arm with the opposite end of the hinged plate.

9. The combination with the head, a bearing arm provided with a cavity in alinement with the head, a hinged plate pivotally connected at one end to the bearing arm, a screw connecting the other end of the hinged plate with the bearing arm, and interlocking 105 plates connecting the head with the hinged plate.

In testimony whereof I have affixed my signature in presence of two witnesses.

CHARLES L. GRODE.
